UNITED STATES PATENT OFFICE

2,504,938

LAMP EXHAUST TUBE BENDING APPARATUS

Gerald S. Quinn, Salem, and Oliver Mann, Danvers, Mass., assignors to Sylvania Electric Products, Inc., Salem, Mass., a corporation of Massachusetts

Application February 27, 1947, Serial No. 731,832

2 Claims. (Cl. 49—22)

1

This invention relates to electric lamps and discharge devices and more particularly to electric lamps and discharge devices which are provided with a glass tubulation for evacuation and gas filling purposes during the manufacturing thereof. This invention is particularly advantageous in the manufacturing of circular lamps, such as circular fluorescent lamps.

An object of this invention is to provide apparatus for bending a glass exhaust tube.

Another object is to provide apparatus for bending a glass exhaust tube during the processing of the device to which it is connected.

A further object is to provide apparatus for bending a glass exhaust tube of a circular lamp during the manufacturing of the lamp.

Further objects, advantages, and features will be apparent from the following description when read in conjunction with the accompanying drawings in which:

Figure 1 is a perspective view of a lamp tube bending apparatus and the exhaust tube bending mechanism of our invention, showing the relative disposition of the several parts thereof before the lamp tube and exhaust tube bending operations.

Figure 2 is a perspective view of the apparatus and mechanism of Figure 1 showing the relative disposition of the several parts thereof after the lamp tube and exhaust tube bending operations.

Figure 3 is an enlarged perspective view of the exhaust tube bending mechanism shown partly in section.

The manufacturing of a circular fluorescent lamp presents many problems which are not confronted in the manufacturing of conventional linear type lamps. The exhaust tube which, during part of the lamp manufacturing process, extends from one end of the lamp, is a source of one of these problems. This is especially true when the lamp electrodes are sealed in the ends of the lamp before the lamp is formed into the finally desired shape.

The exhaust tube bending apparatus of our invention is particularly adaptable for use with the tube forming apparatus shown in the co-pending application of Ralph B. Thomas and Gerald S. Quinn, Serial Number 676,193, filed June 12, 1946, now abandoned. However, its adaptability to other forms and types of apparatus will be readily appreciated by those skilled in the art.

In Figures 1 and 2 we have illustrated one type of lamp tube forming apparatus with which the exhaust tube bending apparatus of our invention may be employed. This lamp tube form-

2

ing apparatus provides a means whereby a helically formed unit of glass tubing, which has had its inner wall coated with luminescent material and electrodes sealed at each end thereof, may be shaped into its final circular form prior to evacuation. The lamp tube unit is a single turn section cut from a helix of glass tubing, with a space between the ends thereof preferably slightly less than the finally required spacing. The pitch of the helix is predetermined so that the ends of each unit cut therefrom will be offset from each other the desired amount. The inner wall of each unit is coated with luminescent material and electrode mounts are sealed in each end thereof. At least one of these mounts is provided with an exhaust tube through which the sealed device may be evacuated.

As may be seen in Figure 1, the exhaust tube 1, which extends from an end 2 of the lamp tube 3, lies in the path through which the other end of the tube 3 will travel during the lamp tube forming operation. The exhaust tube 1 may be bent perpendicular to the axis of the helix by hand bending the exhaust tube 1 before the lamp tube 3 is mounted on the lamp tube bending jig 4. However, we have found this method to be impractical and unsatisfactory. Accordingly, therefore, we have provided mechanical means for effecting the bending of the exhaust tube 1 during the lamp tube forming operation.

Bending of the exhaust tube 1 is accomplished by means of a gravity-operated mechanism mounted on the jig 4. This mechanism, which is shown more in detail in Figure 3, comprises a cradle 5, in which the exhaust tube 1 is disposed, mounted on a pivot shaft 6 which may be disposed at right angles to the top plane of the jig 4, an arm 7 attached at one end thereof to the pivot shaft 6, and a weight 8 attached to the other end of the arm 7. The pivot shaft 6 is mounted in suitable low friction bearings to allow free movement of the shaft in translating the vertical component of the weight 8 into angular motion of the cradle in which the exhaust tube is disposed. The manner in which this operation is performed is described more fully below.

The jig 4 comprises an annular plate 12, an eccentric stop 10 and a clamping arm 11 mounted on the periphery thereof, a fixed stop 9 on the face of the plate 12 and against which the end 2 of the lamp tube 3 abuts, a weighted V-block 13 and a weighted V-block 14. The weighted V-block 13 is slidably mounted on posts 15 which are mounted on and extend substantially perpendicular to the annular plate 12. The V-block 13

is positioned on the end 2 of the lamp tube 3. The weighted V-block 14 is slidably mounted on posts 16 and 17. Post 16 is mounted on the annular plate 12 and post 17 is mounted on a supporting arm 18 which is, in turn, mounted on the annular plate 12. As will be noted from the drawings, posts 16 and 17, unlike posts 15, are not mounted substantially perpendicular to the annular plate 12. The angular disposition of the posts 16 and 17 is calculated to insure the proper disposition of the ends of the lamp tube 3 upon completion of the tube forming operation.

The helically formed unit of glass tubing or lamp tube 3, as shown in Figure 1 is positioned on the jig 4 with the end 2 thereof abutting a stop 9 on the top face of the jig. The tube 3 is then centered with reference to a line running through the center of the circle which it defines and the center of the space between the ends of the tube as finally formed. An eccentric stop 10 mounted on the periphery of the jig is then adjusted to cause it to engage the tube 3 and a clamping arm 11, pivotally mounted on the eccentric stop 10, is swung in to lock the tube in position.

The V-block 13 is positioned on the end 2 of the lamp tube 3 and the V-block 14 is positioned on the end 19 of the lamp tube. In order to prevent the weight of the V-block 13 from distorting the end 2 of the lamp tube 3 during the tube forming operation a means is provided for relieving the tube 3 of this weight. This means comprises an elongated screw 20 which extends through the V-block 13 into a post 15, and a wing nut 21. A similar arrangement is provided to prevent the weight of V-block 14 from distorting the end 19 of the tube 3 after the tube forming operation has been completed. This arrangement comprises an adjustable screw 22 mounted in the free end of a bracket 23, which has an end thereof attached to the V-block 14. The free end of the bracket 23 lies above the V-block 13. The screw 22 is adjusted so that it will engage the top of the V-block 13 when the tube forming operation has been completed.

The jig 4 with the lamp tube 3 properly positioned on and secured thereto, and the V-blocks 13 and 14 positioned, as described above, on the ends 2 and 19 of the tube 3, is placed in a heating chamber where it is exposed to heat of a degree calculated to cause the glass, of which the tube is made, to soften and become plastic. When the glass softens the weighted V-block 14 will slowly, by force of gravity, push the elevated end 19 of the tube 3 downwardly until the entire tube rests on the annular plate 12 and the ends 2 and 19 thereof are in proper circular alignment and spaced the desired predetermined distance. In placing the jig, with the tube seated thereon, in the heating chamber, we have found it advantageous to elevate the side of the jig which supports the raised end 19 of the tube 3 about 8 degrees. This canting of the jig is particularly advantageous in cases where the distance between the ends of the tube 3 is greater than the finally desired distance because, when the heated glass becomes plastic, gravity will cause the end 19 of the tube 3 to move toward the end 2 of the tube, thus causing it to assume a position which will finally locate it at the desired predetermined distance from the end 2.

As mentioned above, an object of this invention is to provide a mechanical means for bending the exhaust tube 1 out of the path of the end 19 of the lamp tube 3, and assume a position which

will facilitate the further processing of the tube 3. The mechanism of our invention accomplishes this during the lamp tube bending operation, while the jig is canted in the manner described above.

When the tube 3 is mounted on the jig 4, the exhaust tube 1 is disposed in the cradle 5 of the exhaust tube bending apparatus. The temperature of the oven in which the jig and tube is disposed is sufficiently high to effect a softening of the lamp tube 3 and the exhaust tube 1. The exhaust tube bending mechanism remains stationary until the exhaust tube 1 becomes sufficiently pliable to enable the vertical component of the weight 8 to be translated into angular motion of the cradle 5 in which the exhaust tube 1 is disposed, through the rotary motion of the shaft 6. The weighting of the exhaust tube bending mechanism is calculated to effect the withdrawal of the exhaust tube 1 from the path of the end 19 of the lamp tube 3 before the end 19 has moved down into position on the annular plate 12. A stop 24 mounted on the stop 9 is provided to exactly define the end of the path through which the cradle 5 travels and thus insures the desired disposition of the exhaust tube upon completion of the exhaust tube bending operation.

The exhaust tube bending mechanism, which is shown in detail in Figure 3, is supported by a bracket 25 which is mounted on the bottom of the annular plate 12. The pivot shaft 6, to which the exhaust tube cradle 5 and the moment arm 7 are fixedly connected, is mounted in suitable low friction bearings to permit free movement thereof in translating the vertical component of the weighted member 8 on the outer end of the moment arm 7 into angular motion substantially paralleling the surface of the annular plate 12 of the jig 4. The upper portion of the shaft 6 is mounting in bearing 26 which, for convenience, has been formed integral with stop 24. The shaft 6 extends through the annular plate 12 and the lower end thereof is mounted in a suitable low friction bearing, such as a lava cup 27, for example. The lava cup 27 is seated in a bearing support 28 on the outer end of the bracket 25. The bearing support 28 is provided with a threaded aperture 29 for a screw 30. The screw 30 provides a means for properly positioning the lava bearing 27 and for adjustments thereof which may be necessary due to wear.

A collar 31 on an end of the cradle 5 serves as the means whereby the cradle 5 is fixedly connected to the shaft 6. The moment arm 7 is connected to the shaft 6 by means of a bracket 33 which has a collar 32 on one end thereof and a collar 34 at the other end thereof. The collar 32 is fixedly connected to the inner end of the arm 7 and the collar 34 is fixedly connected to the shaft 6.

Although we have shown and described the exhaust tube bending mechanism of our invention as comprising an exhaust tube cradle fixedly mounted on a pivotal shaft, it will readily be understood by those skilled in the art that if desired one may pivotally mount the exhaust tube cradle itself. For example, the exhaust tube cradle may be pivotally mounted on ball bearings, pivot bearings or other well-known means for supporting a rotatable member, without departing from the spirit of our invention. In selecting a means to effect rotation of the exhaust tube cradle, it is desirable that one select materials which will not be adversely affected by operating conditions to which the mechanism may be sub-

jected, such as the high temperature necessary to soften the exhaust tube to a pliable state, for example.

What we claim is:

1. Apparatus for bending an electric lamp exhaust tube which has been heated to a pliable state, said apparatus comprising a mounting surface; a rotatable shaft supported by said mounting surface; a cradle for said exhaust tube fixedly connected at one end thereof to said shaft; a moment arm fixedly connected at one end thereof to said shaft; and a weighted member disposed at the other end of said moment arm, the relative disposition of the mounting surface, shaft, cradle, moment arm and weighted member being adapted to produce rotational movement of said shaft and said cradle.

2. In combination, a jig for forming a substantially circular lamp tube in which all points on the axis of the lamp tube are in the same plane, from a segment of a helix of glass tubing having electrodes sealed therein at the ends thereof and an exhaust tube projecting from one of said sealed ends and substantially perpendicular to

the plane thereof, said jig comprising a base member, means for positioning said lamp tube on said base member, means, upon the application of heat to the lamp tube, to bring the axis of the lamp tube into a plane, means for causing the ends of said lamp tube to be disposed a predetermined distance from each other, and apparatus for bending said exhaust tube when said tube is heated to a pliable state so that a portion thereof will lie along a line which is substantially in the plane of and radial to the lamp tube axis circle and substantially centered between the ends of said circular lamp tube.
